UNITED STATES PATENT OFFICE

2,465,362

BOOT DRIER

Sam C. Elliott, Hermosa Beach, Calif.

Application April 24, 1946, Serial No. 664,658

4 Claims. (Cl. 34—104)

1

This invention relates to boot dryers.

Although the invention may be used to advantage to dry boots for persons in various occupations, it is more particularly intended for the use of sportsmen and travelers who need a portable compact device which can be used to dry their boots whenever they happen to become wet by reason of wading too deeply through water, or because of having been exposed to rainy weather.

A further object of the invention is to provide a boot drier which is well adapted for having heat supplied to it by means of electric lamps.

More specifically speaking, it is an object of the invention to provide an improved set of boot-supporting tubular members which are compactly housed within a portable chest, and which may quickly and conveniently be removed from, and then mounted upon, said chest in a boot-supporting position wherein they direct the heat in an advantageous manner to the interior surfaces of the boot supported upon them to be dried.

Other objects, advantages and features of invention will hereinafter appear.

Referring to the accompanying drawing, which illustrates a preferred embodiment of the invention,

Fig. 1 is a side elevation of the apparatus in its operative position, parts within the casing being indicated by dotted lines, while broken lines indicate the outlines of a pair of boots mounted in the position for being dried.

Fig. 2 is a perspective view of the casing containing the boot-drying elements.

Fig. 3 is a vertical section on line 3—3 of Fig. 2.

Fig. 4 is a section on line 4—4 of Fig. 2.

Fig. 5 is a section showing a fragment of the basal portion of one of the tubular boot-supporting members, the plane of section being indicated by line 5—5 on Fig. 6.

Fig. 6 is a plan view of the structure shown in Fig. 5.

Fig. 7 is an approximate elevation showing somewhat in perspective the upper member of one of the boot-supporting tubes, the central portion of the tube being broken away in order to contract the length of the view.

Fig. 8 is an approximate elevation showing somewhat in perspective an intermediate member of the boot-supporting tubes, the central portion being broken away in order to contract the length of the view.

Referring in detail to the drawing, a portable

2

box or chest 10 is provided, having one end wall 11 swingably fastened to the top wall 12 by means of hinges 13, thus providing a spacious door opening and door therefor. As best shown in Fig. 3, within said box are demountably supported four stove-pipe-like tubes 14 of the intermediate type (see Fig. 1), two 14a, of the basal type, and two 14b of the top or upper terminal type, paired spring arms 15 being carried by the box 10 to hold all of said tubes (eight in number) in their stored demountable condition within the box 10. The paired arcuate spring arms 15 are arranged in each pair with the concave sides of the arms directed toward each other and so positioned as to receive between them the pipe joints when the latter are inserted through the door opening in an endwise manner.

The box 10 is provided, in an endwise relation to the aforesaid mounted tubes, with the already mentioned hinged door 11 which completely overlies one end of the box 10 so that when said door is fully open any of the contained tubes can be readily removed. Said door has in its free, lower edge a notch 16 to accommodate the electric supply cord 17 (carrying plug-in terminal 17a) of the heater 18 (in this case an electric lamp) secured centrally to the inner side of that end of the box that is opposite to said door 11, the pipe-joint supporting arms 15 being so arranged as to leave the latter end portion of the quadrilateral box 10 unobstructed.

In each set of the assembled tubes shown in Fig. 1, the lowest tube 14a is provided at its lower end (see Fig. 8) with outwardly directed diametrically opposite locking ears 20 to underlie and interlock with an annular locking plate 21 fastened in a countersunk manner to the rather thick top wall 12 of the box 10, in register with each circular air vent opening 22. The diameter of said opening 22 is slightly less than the internal diameter of said annulus 21, a supporting ledge 23 being thus provided for the four-joint foot-supporting tube. Between said ledge and annulus results an annular recess 25, the aforesaid pipe ears 20 being insertable into said recess through diametrically opposite interior notches 26, in said annulus sufficiently large to admit said ears 20 preparatory to the ear-carrying pipe section 14a being turned to a locked-on relation as indicated by the dotted line position of the ears 20 shown in Fig. 6.

Each four-joint boot-supporting tube has each of its joints except its uppermost joint 14b formed with a crimped, slightly tapered upper end por-

tion 14c to telescope in a stove-pipe fashion into the next joint above. The upper part of the top joint 14b is not crimped or tapered but is provided with means 30 for interiorly supporting a boot in a spaced, air-circulating relation to the entire tubular structure upon which the boot is mounted. Said means 30 is shown as a bail with the end portions of its arms pivoted at 31 to the upper pipe section in a downwardly spaced relation to its upper end, thus leaving room for the longitudinal side grooves 32 consisting of inward deflections of the sheet metal forming said pipe section into which the arms of said bail spring yieldingly to hold the bail in its upswung, boot-supporting position. The downswung position of the bail indicated in dotted lines in Fig. 7, renders the pipe section 14b shorter for storing in the box 10.

The portable box 10 is shown provided in the center of its top side with a foldable handle 35 so that it may be conveniently carried by the user. The swingable door 11 carries near its lower edge an internal catch member 36 which yieldingly interlocks with a stationary catch element 37 when the door is closed.

In preparing the device for use the operator will first withdraw the pipe joint sections 14a from the box 10 and, after placing said joints in their upright locked-on position, will telescope onto them the intermediate joints 14, 14, and then will add the uppermost joints 14b and then upswing the spacer loops or bails 30. The pair of boots 39 to be dried may then be put in place as shown, when it only remains to plug in the electric terminal connection 17a into a current supply fixture. The door notch 16 admits air to replace the rising heated air, but if desired the door may be held partly open by any suitable means.

The two tubular boot-supporting tubular structures should have external diameters considerably less than the internal diameters of the leg portions of the boots to be dried, so that the drying air will pass down along the interior surfaces of said leg portions of the boots, which are supported with their lower (normally upper) ends spaced somewhat above the top of the box 10.

I claim:

1. In a boot drier, a tubular stove-pipe-like member of rigid sheet material having a swingable resilient bail-like boot rest attached to one of its end portions, said member having diametrically opposite recesses in its body portion positioned yieldingly to hold said bail at times in an outswung boot-supporting position, and means to support said member in a substantially vertical position with its bail-carrying end uppermost, said recesses consisting of inward deflections of the tubular sheet material.

2. In a boot drier, a quadrilateral box having a door opening occupying the greater part of one of the rectangular sides of the box, a plurality of boot-supporting tubes demountably supportable upon said box in upstanding positions and in communication with the interior thereof, said tubes each consisting of disconnectible stove-pipe-like joints which when disconnected from each other are insertable through said door opening for storage within said box, an assembly of arcuate mounting arms for said pipe joints, said arms being attached interiorly to said box in pairs con-

sisting of two adjacent arms with their concave sides directed toward each other and positioned to receive between them and support the pipe joints when the latter are inserted individually through the door opening in an endwise manner, said paired arms with said tubes mounted therein leaving an unobstructed space in the inner side of the box opposite to said door opening, and an electric lamp mounted inside the box upon said inner side thereof in said unobstructed space.

3. In a boot drier, a set of stove-pipe-like tubes of rigid sheet material, a box having within it means for so supporting said set of tubes that they are manually demountable and removable from said box, a rather thick like pipe-support wall carried by the upper portion of said box, said wall having through it an aperture communicating with the interior of the box, an annular locking plate fastened in a countersunk manner to said pipe-support wall in register with said aperture, said set of tubes being connectible in the fashion of stove pipe joints superjacent to said locking plate and in an interlocking relation therewith, means carried by the free end of the lowermost of said tubes of a so connected set to interlock with said top wall in registration with the aperture of the latter, said means comprising diametrically opposite locking ears carried by said lowermost tube at its lower end to underlie and interlock with said annular locking plate, the diameter of said aperture being slightly less than the internal diameter of said annular locking plate, thereby providing a supporting ledge for said set of tubes, there being an annular recess resulting between said ledge and annular plate and diametrically opposite interior notches in said annular locking plate sufficiently large to admit said ears preparatory to the ear-carrying tube being turned to a locked-on position within said annular recess, and mounting means for a boot carried by the free end of the uppermost tube of said set to support the boot in a spaced air circulatory relation to said set of tubes.

4. The subject matter of claim 2 and, said mounting means comprising a swingable resilient bail-like boot rest attached to the upper end of said uppermost tube, the latter tube having diametrically opposite recesses in its body portion positioned yieldingly to hold said bail at times in an upswung boot-supporting position, said recesses consisting of inward deflections of the tube's sheet material, and an air heater mounted within said box.

SAM C. ELLIOTT.
